(57) **CLAIM**

The ornamental design for a speaker transducer housing, as shown and described.

DESCRIPTION

FIG. 1 is a perspective view of a speaker transducer housing showing my new design;

FIG. 2 is a bottom plan view thereof;

FIG. 3 is a top plan view thereof;

FIG. 4 is a front elevational view, the rear elevational view being a mirror image thereof; and,

FIG. 5 is a side elevational view, the opposite side elevational view being a mirror image thereof.
